UNITED STATES PATENT OFFICE

CHESTER L. DAVIS, OF WASHINGTON, DISTRICT OF COLUMBIA, ASSIGNOR TO WIRED RADIO, INC., OF NEW YORK, N. Y., A CORPORATION OF DELAWARE

SIGNALING SYSTEM

Application filed July 10, 1928. Serial No. 291,538.

My invention relates to signaling systems in general and more specifically to receiving systems wherein thermionic vacuum tubes are employed.

5 An object of my invention is to provide a system for the reception of high frequency signaling energy employing thermionic vacuum tubes whereby all batteries as a source of energy are dispensed with.

10 Another object of my invention is to provide a system for the reception of high frequency signaling energy whereby the necessary energy for energizing the thermionic vacuum tubes is derived from electrodynamic

15 means and a source of tension motive power. A further object of my invention is to provide a system for energizing thermionic vacuum tubes employed in amplifier and transmitter circuit arrangements.

20 Other and further objects of my invention will appear from the specification to follow and by referring to the accompanying drawing in which:

Figure 1 is a representation of the 25 embodiments of my invention; and Fig. 2 is a representation of one embodiment of my invention in greater detail.

In signaling systems wherein thermionic vacuum tubes are employed for the generation, amplification and rectification of high frequency electrical energy, it is necessary to employ a source of electrical energy for the cathode and anode circuits. Batteries have been employed heretofore for this purpose and are satisfactory when fully charged with energy. It becomes necessary to renew the batteries or have them recharged and this is a considerable inconvenience and expense. The power systems employed for 30 commercial power and lighting have been employed but the latter is not available wherever it is desired to operate high frequency signaling systems. It is possible to operate signaling systems without employing the conventional thermionic vacuum tube but the efficiency of the thermionic vacuum tube is sufficient justification for its use in preference to other possible systems. In the signaling system of my invention all batteries as 35 a source of power are dispensed with.

In the signaling system of my invention electro-dynamic means are employed in combination with a mechanical tension source of energy for producing the necessary electrical energy to energize the circuits of thermionic vacuum tubes. By referring to Fig. 1 a better understanding can be had of the system I employ. Fig. 1 illustrates a radio receiving system in its entirety. Thermionic vacuum tubes 1, 2 and 3 are employed as a radio frequency amplifier, rectifier and audio frequency amplifier respectively. A source of high frequency energy is received by any convenient collecting system and coupled to the input circuit 12 by connections 4. A capacity 16 is employed for adjusting the frequency characteristics of the grid or input circuit of thermionic vacuum tube 1 to the frequency value of the incoming signaling energy. The amplified radio frequency signaling energy is amplified and transferred by inductance system 13 to thermionic vacuum tube detector 2 which is caused to rectify the radio frequency energy by reason of grid leak and condenser 14. The audio frequency component of the rectified signaling energy is coupled to thermionic vacuum tube 3 through transformer 10. The output energy of thermionic vacuum tube 3 is coupled to reproducer 21 by means of capacity 25 and impedance 11. Electrodynamic source of energy 6 supplies the proper electrical potential to the cathode and anode circuits of thermionic vacuum tubes 1, 2 and 3. A resistor 26 may be employed in circuit with the output of electrodynamic source of electrical energy 6 for reducing the potential to either of the cathode or anode circuits. Electrodynamic source of energy 6 may be a dynamo-electric machine having field and armature circuits and commutators 8 and 7 with collecting brushes associated therewith. Such a dynamo-electric machine may be of the series or shunt wound type, the type employing a common field and separate armature windings, or separate armature and field windings for both cathode and anode supply. Connections are accomplished by means of terminal board 9. Commutators 7 and 8 are large in diameter and each comprise a large number of commutator seg- 40 45 50 55 60 65 70 75 80 85 90 95 100

ments. Capacity 17 is of large value and sufficient to prevent fluctuation of potential in the cathode and anode circuits caused by commutation. Dynamo-electric machine 6 is mounted on a sound deadening base 24. The 5 armature of dynamo-electric machine 6 is rotated by a mechanical tension source of energy 28. Mechanical tension source of energy is energized by resilient means 18. The resilient means may be compound whereby sufficient tension is maintained to rotate the armature of dynamo-electric machine 6 for a greater period of time. Resilient means 18 is energized by means of crank 29 at occasional intervals thereby restoring the mechanical 10 tension. Mechanical energy is transferred from resilient means 18 to gear system 22 and shaft 30. Shaft 30 is mechanically connected to the armature of dynamo-electric machine 6. Governor 20 controls the speed of rotation 15 of shaft 30, connected to the armature of dynamo-electric machine 6, as determined by the position of movable arm 19. The governor 29 carries a friction disc 31 which bears against the friction face 32 at the end of arm 19. Arm 19 is pivoted at 33 on bracket 23 and may be moved to predetermined positions and latched in position by means of toothed ratchet 34. Movable arm 19 thereby controls the potential from dynamo-electric machine 20 20 by controlling the operation of governor 20 and the rotation of the armature. This provides an efficient and effective volume control by controlling the potential supplied to the 25 cathode and anode circuits. Gear system 22 is illustrated as mechanically coupling the energy from resilient means 18 to shaft 30, however, it is obvious that a pulley and belt system would cause less noise in the transfer 30 of the mechanical energy. A weight system 35 may be employed instead of the resilient means illustrated. Dynamo-electric machine 6 and tension motor may be enclosed in any suitable sound deadening compartment and 40 isolated from the receiver proper as illustrated in Fig. 2.

In Fig. 2 of the accompanying drawing the source of dynamo-electric energy 6 and tension motor 28 are illustrated in greater detail. A mechanical tension is obtained by means 50 of a compound resilient element 18. A tension is produced by means of crank 29. The mechanical tension is released by means of shaft 30 and gear 22. Mechanical tension is 55 transferred to shaft 30 on which governor 20 is mounted. Governor 20 is controlled by disc 16 and control member 19. A rotary motion is transmitted to the armature of dynamo-electric machine 6. Commutators 7 60 and 8 are connected to the armature and brushes 10, 11, 12 and 13 and provide means for transferring the generated electrical energy to terminals 9. Field windings 14 and 15 are illustrated connected in shunt with 65 brushes 10, 11 and 12, 13 respectively. Sound

absorbing base member 24 provides means for deadening the noise of mechanical motion. Capacity 17 is employed for causing a substantially constant supply of energy to terminals A and B. Terminals A and B are 70 provided for connecting the generated electrical energy with cathode and anode circuits external to the generating system.

The advantages of the signaling system of my invention include: 1. A compact and 75 portable arrangement suitable for aircraft communication. 2. Radio broadcast receiving systems whereby loud speaker volume can be obtained without the necessity of employing batteries. 3. The operation of remote 80 control broadcast amplifier systems. 4. The operation of complete transmitting and receiving systems, employing thermionic vacuum tubes, in isolated locations.

In the accompanying drawing a radio frequency amplifier, detector and audio frequency amplifier are illustrated. It is obvious that any number of thermionic vacuum tubes may be employed. Only energy supply 90 for the cathode and anode circuits is illustrated. It is obvious that any required electrical energy may be produced. Gear mechanism is illustrated for transmitting mechanical energy. It is likewise obvious that a pulley and belt system may be employed. I realize that many modifications of my invention are possible without departing from the spirit of my invention as defined in the appended claim. It is not intended that my invention be limited to the accompanying 95 drawing or to the foregoing specification but only as defined in the appended claim.

What I claim as new and desire to secure by Letters Patent of the United States is as follows:

A portable radio receiving apparatus comprising an electron tube amplifier connected to a sound reproducer, means enclosing said amplifier, a tuning control for said amplifier projecting beyond said means and operative from the exterior thereof, a generator for energizing the anode and cathode circuits of said amplifier, a spring motor adapted to be periodically wound for the storage of tension energy therein, a speed multiplication gear connecting said spring motor with said generator, a governor connected with said speed multiplication gear, and a control extending outside of said enclosing means for modifying the effect of said spring motor upon said generator for simultaneously regulating the energization of the anode and cathode circuits of said amplifier by said generator for correspondingly controlling the volume of sound reproduced by said sound reproducer.

In testimony whereof I affix my signature.

CHESTER L. DAVIS.
